CLAIM

The ornamental design for a keyboard folio as shown and described.

DESCRIPTION

1. Keyboard folio
- 1.1 : Perspective
- 1.2 : Perspective
- 1.3 : Front
- 1.4 : Back
- 1.5 : Left
- 1.6 : Right
- 1.7 : Top
- 1.8 : Bottom

1.1 is a top, rear, left side perspective view of a keyboard folio, showing our new design; 1.2 is a bottom, front, right side perspective view thereof; 1.3 is a front elevation view thereof; 1.4 is a rear elevation view thereof; 1.5 is a left side elevation view thereof; 1.6 is a right side elevation view thereof; 1.7 is a top plan view thereof; and 1.8 is a bottom plan view thereof; the broken lines are included to show features that form no part of the claimed design.

1 Claim, 8 Drawing Sheets
